UNITED STATES PATENT OFFICE.

LEMUUEL COBURN AND WILLIAM J. SUMNER, OF HOLYOKE, MASSACHUSETTS,
ASSIGNORS TO THE COBURN TROLLEY TRACK MANUFACTURING COMPANY, OF SAME PLACE.

DOOR FOR CARS OR OTHER STRUCTURES.

SPECIFICATION forming part of Letters Patent No. 432,225, dated July 15, 1890.

Application filed July 15, 1889. Serial No. 317,597. (No model.)

To all whom it may concern:

Be it known that we, LEMUEL COBURN and WILLIAM J. SUMNER, citizens of the United States, both residing at Holyoke, in the county 5 of Hampden and State of Massachusetts, have invented new and useful Improvements in Doors for Cars or other Structures, of which the following is a specification.

This invention relates to sliding doors and 10 trolley-hangers therefor, the same being particularly applicable for use for freight-car doors, although well adapted for use for barn and other doors; and the invention consists in the construction and combination of parts, 15 all substantially as will be hereinafter more fully described, and finally set forth in the claims.

Reference is to be had to the accompanying drawings, forming part of this specification, 20 in which the invention is illustrated, and in which similar letters of reference indicate corresponding parts in all the views.

Figure 1 is a side elevation of a portion of a freight-car and its door, the same being 25 shown as closing the doorway, and the trolley-hangers for the door are also shown. Fig. 2 is a horizontal section of parts shown in Fig. 1, taken on the line $x-x$. Fig. 3 is a vertical central longitudinal section, on a larger 30 scale, of the trolley-track, a roller-carrier therein, and a hanger on which the door is supported. Fig. 4 is a perspective view, also on a larger scale, of a short section of the trolley-track. Fig. 5 is a vertical cross-sectional view of Fig. 1, but on a much larger 35 scale than said figure, with the door closing the doorway or opening, the plane of such section being indicated by line $y-y$, Fig. 1; and Fig. 6 is an enlarged vertical cross-sectional view similar to Fig. 5, but with the 40 door swung out of its flush relation with the side of the car and ready to be slid away from the front of the doorway. Fig. 7 is a side view of one of the hangers and one of 45 the trolley-rollers.

In the drawings, A represents the side wall of a freight-car or other structure having the opening or doorway a , above which the trolley-track C is secured in a horizontal posi-

tion, and B is the door to fit in the jambs of 50 said doorway. Said trolley-track, as shown, consists of a tube, generally of rectangular cross-section, having the lower edges curved in toward the median line and then turned upward, so that the bottom of the tube has a 55 trough b at each side of a central longitudinal opening d . The said trolley-track is to be of a length equal to about twice the width of 60 the door, and is supported on the side of the car in any suitable manner, a practical and desirable form for such support being shown at x , which consists of a holder or casting having inclosing-walls on three sides, and also having on its under side opposing lips c , all so that the trolley-track may be closely embraced and 65 supported thereby, said casting having ears e , through which they are attached to the wall of the car, the opening between the said lips c permitting free passage from end to end 70 of the hanger supported on and carried by the roller-carrier D. Said supporting-castings are to be provided at suitable intervals in the length of the track, as may be deemed necessary or desirable.

The roller-carrier consists of a pair of rollers 75 10, united by a common axle 12, said rollers by their peripheries rolling in said troughs b of the trolley-tracks.

E & represent a pair of hangers, each suspended by its upper end from a roller-carrier 80 and by its lower end pivotally connected to the door, so that the door may have bodily a swinging motion outwardly (or at right angles to the wall of the car, said door always being maintained practically parallel with 85 said wall) and to an extent greater than the thickness of the door. The connection of the hanger with the roller-carrier is by forming the hanger of T shape, the cross portion 13 thereof being slotted, as at 14, by which slot 90 the axle of the roller-carrier is engaged with the hanger. While it is preferable that the hanger be of the form shown and have an elongated slot, it may be formed with practicability, as shown in the view Fig. 7, with 95 merely an eye at its upper end to engage the roller-axle. The carrier is formed by separate rollers axially drilled and driven onto

the ends of the axle, and the connection of the hanger by its slot or eye with said axle is made before the parts of the roller-carrier are united.

- 5   *g* represents a lug at one outer side of the doorway, overlying slightly the opening, serving to maintain the corresponding edge portion of the door in its closed disposition, and a hasp *h*, bolt, or other locking or confining contrivance is to be employed at the opposite edge of the door or doorway. Assuming that the door is closed, as shown in Figs. 1, 2, and 5, and desiring to open same by unfastening the hasp, &c., and swinging the edge of the 15 door on which such hasp is carried outwardly clear of the adjacent jamb, the hanger toward such jamb at such time swinging outwardly with the door permitting said movements. The door is then slid longitudinally and horizontally until its rear edge has passed the lug *g*, when such rear end portion of the door is also pulled outwardly, so that the entire door then ranges parallel with the side wall, being outside thereof, and then the door may be 25 slid, through the medium of the hangers and roller-carriers, between it and the trolley-track along the side of the car or other structure and entirely away from the front of the doorway. It will be noted that the thickness of 30 the hanger adjacent its point of connection with the axle of the roller-carrier is less than the distance between the rollers of said carrier, and the opening in the hanger is of such size that the axle may fit the same loosely, 35 and therefore the hanger has in substance a pivotal connection with said roller-carrier, whereby it is capable of being swung in a plane at right angles to the vertical plane of travel of the said roller-carrier.
- 40   A lug *j* (shown near the forward lower corner of the doorway) is desirable as determining the extent of outward drawing necessary for the car-door to carry it clear from the plane of the walls of the car and to prevent excessive outward movement, and another and angularly-formed lug *k* (shown on the side of the wall at a proper distance from the door-opening) limits the endwise slide of the door when it has been slid sufficiently to 45 clear the doorway, and the said lugs *j* and *k* maintain the door when open in a close disposition against the side of the car and prevent any flapping or swinging thereof. As shown at *l* in Figs. 1, 5, and 6, the door is 50 slotted vertically, within which slots the said hanger-bars may generally lie, and by the provision of which no impediment to the

swinging motion of the door on the hangers or the hangers with relation to the door may be had, and in practice caps or guards, as 60 shown at *G*, are to be provided for inclosing said hanger-bars and covering the said slots in the door. In Fig. 1 one of said caps is shown as removed.

Under the construction and arrangement 65 of parts described the present door possesses the features of a flush and sliding door—that is, when the door is closing the doorway its outer side is flush with the side of the car and yet it is capable of being moved to be 70 slid, while heretofore flush doors have usually been swung from and by their one edge on hinges.

What we claim as our invention is—

1. The combination, with the wall of the 75 car or other structure having a doorway and a double-way trolley-track thereabove, of a door, the carriers, each comprising a pair of rollers and a uniting-axle supported and movable in the ways of said trolley-track, and 80 hanger-bars having a thickness less than the distance between said rollers and connected with and supported from the axles of said roller-carriers, whereby they may have a laterally-swinging motion thereon, said hangers 85 also being pivotally connected with said door, substantially as described.

2. The combination, with the wall of the 90 car or other structure having a doorway and a double-way trolley-track thereabove, of a door, the carriers, each comprising a pair of rollers and a uniting-axle supported and movable in the ways of said trolley-track, hanger-bars supported from the axles of said roller-carriers and pivotally connected with said 95 door, and caps *G*, for inclosing said hanger-bars, substantially as described.

3. The combination, with the wall of the 100 car or other structure having a doorway and a double-way trolley-track thereabove, of a door having vertical slots therein, the carriers, each comprising a pair of rollers and a uniting-axle supported and movable in the ways of said trolley-track, and hanger-bars supported from the axles of said roller-carriers and pivotally connected with said door and adapted to be disposed in said slots, substantially as described.

LEMUEL COBURN.
WILLIAM J. SUMNER.
